UNITED STATES PATENT OFFICE.

ANDREAS P. LUNDIN, OF BAYSIDE, NEW YORK.

LIFE-BOAT.

1,249,645.

Specification of Letters Patent. Patented Dec. 11, 1917.

Application filed February 20, 1914. Serial No. 819,884.

To all whom it may concern:

Be it known that I, ANDREAS P. LUNDIN, a citizen of the United States, and a resident of Bayside, borough of Queens, county of Queens, and State of New York, have invented certain new and useful Improvements in Life-Boats, of which the following is a specification.

This invention relates to improvements in life boats.

By the use of my invention I am enabled to produce a life boat, which, in addition to its constructional characteristics of great strength, durability and substantial indestructibility, will have a shell or hull provided with a well having seating devices for passengers, which hull, without use of ballast, heavy keels, center boards or other similar devices, will be substantially non-capsizable and extremely stable and will have a passenger protective metallic housing of a peculiar non-water resisting and highly unstable conformation erected above the hull inclosing the well and provided with water-tight closures so as to form with said well a buoyant water-tight compartment, whereby in case the boat is capsized by a wave during launching or otherwise, it will quickly right itself and regain its normal position, the self-righting of the boat being further insured because the hull, on account of its conformation and its seating devices, has a great preponderance over the housing of properly distributed weight and also has buoyant air chambers and combination fenders and buoyant sides, which not only add weight but by reason of their buoyancy assist in the self-righting of the boat.

Furthermore such a housing will provide for the passengers adequate shelter, protection, air, light, observation and rowing facilities and ready ingress and egress, and when in normal position its peculiar novel contour will tend to break and lessen the shock of contacting waves.

Another novel feature of my invention is the provision in a passenger protecting housing of side ports or window apertures for the admission of light and the transference of passengers in case of necessity, having row-lock notches formed in the lower edges thereof; water-tight closures for the ports

and independent water-tight closures for the row-lock notches hinged to the port closures.

In the preferred form of my invention the hull has a wide substantially flat bottom with flat sides, the contour of the latter being rounded out by combined supplementary sides and fenders of balsa wood, has a double bottom with intermediate air chambers and has rounded or curved front and stern portions, the peculiar conformation of the hull being exceedingly stable without the use of heavy keels, center boards or the like, which not only take up valuable space which may be otherwise usefully occupied, but prevents the ready handling of the boat on ship board, said conformation also permitting the boat to be superimposed or nested above a boat of the type which has a similar shaped hull and collapsible superstructures or weather-boards, such as described in my former application Serial No. 694,432, and may be readily handled by the forms of davits and other boat handling devices at present in use; entrance decks fore and aft substantially level with the sides of the hull; a well provided with side benches and thwarts extending from the fore to the aft deck and a passenger protective housing erected above said well having water-tight closures and preferably being of the rigid construction illustrated, which consists of a series of metallic plates abutting each other, each plate having an integral marginal semi-circular groove contiguous to its abutting edge, the abutting plate lapping said groove and riveted thereto on opposite sides of the groove, the housing being reinforced and supported by transverse ribs comprising metal strips or bars having a U-shaped central portion and laterally projecting flanges to permit riveting to the shell plating.

In the accompanying drawings, in which similar reference characters designate corresponding parts throughout the several views,

Figure 1 is a plan view of my improved self-righting boat;

Fig. 2 is a cross-section on the line 2—2 of Fig. 1, looking in the direction of the arrow;

Fig. 3 is an enlarged longitudinal section 105 of the aft half of said boat;

Fig. 4 is a detailed sectional view of the ventilating tubes preferably employed by me;

Fig. 5 is a detail of my preferred construction of window closure;

Fig. 6 is a transverse sectional view of a modified form of boat embodying my invention; and

Fig. 7 is a view in plan of another slightly modified form.

Referring now to these drawings 1 indicates a hull or shell of metal or other suitable material having a substantially flat bottom 2 and provided with a well or passenger seating compartment 3, a double bottom or floor 4, the space between the bottom 2 and floor 4 of the well being divided into a series of air-tight compartments or chambers 5 by suitable dividing partitions 6, and 15 flat sides 7 terminating in rounded bow and stern portions 8 and 9 respectively, having exposed decks 8^a-9^a substantially level with the sides of the hull.

As illustrated in Figs. 1, 2 and 3, the well 25 or passenger seating compartment 3 is oblong or box shaped in configuration and is provided at its extreme upper edges with marginal seats 10 and thwarts or cross seats 11 which assist in reinforcing the shell to 30 form a structure of great strength and rigidity. A series of suitable bailing tubes 12 preferably connect openings in the floor of the well and the bottom of the boat, which tubes may be provided with any suitable 35 valve mechanism to permit water to be discharged but to prevent water to enter said well.

The flat metallic sides are preferably 40 rounded out by what I shall term supplementary sides 7^a of highly buoyant material and preferably of balsa wood which has been treated so as to close its pores and make it water-tight. These supplementary sides are preferably detachably secured to the hull 45 by means of straps 7^b, extend both above and below the water-line, and the top edge of the same being squared and covered with a side strip 7^c so as to form a narrow deck extending laterally at opposite sides of the 50 well.

The thwarts and side seats are also preferably braced by means of struts 13-13 at opposite sides which are connected by diagonally extending connecting rods 14 having turn-buckles 15-15 and also by a centrally located strut 16, thus preventing the sagging of the seats and further reinforcing the hull.

A passenger protective housing 17 preferably formed of sheet metal is, as shown, 60 erected above said well, is of less length than the hull and has a rounded or semi-spherical conformation so that, if the boat capsizes, the surface presented to the water will 65 be as unstable and non-water-resisting as pos-

sible. Said housing is preferably provided with entrance or exit ports 18-18 at the front and rear opening in the decks 8^a-9^a and said ports are provided with watertight closures 19-19 having suitable handles or knobs 20 with means for compressing a watertight packing 21 inclosed in a marginal groove in the closure and surrounding the port. Said housing is, as illustrated, provided with a series of glazed side ports 22, each having a glazed watertight closure 23. As illustrated, said ports are elliptical in shape and provided with two circular window lights 24-24^a, the closure being hinged to the upper edge of the port and provided at its lower edge with thumb screws 25-25^a, or other appliances for applying pressure on a watertight packing surrounding said port.

The lower edges of each of said ports are 75 preferably provided with a row-lock notch 26, which notch is provided with a watertight closure 27 hinged on the closure of the port 25, said row-lock closure 27 being 80 also provided with a thumb screw or other 85 pressure applying device 28.

I also preferably provide in the ceiling 90 of said housing a series of ventilating tubes 29 adapted normally to remain in open position for the admission of air to said housing 95 but to close automatically if the boat is capsized to prevent ingress of water therethrough. As shown, each tube 29 is provided with a valve 30 pivoted eccentrically as at 100 31, the short side of such valve being provided with a weight 32 adapted normally to retain the same in open position, a stop pin 33 being also preferably provided to prevent abnormal swinging of the valve. Obviously, 105 when such ventilating tube is inverted the valve 30, owing to the position of the weight 32, will automatically close upon its seat 34. Said ventilating tubes are also preferably provided with a rain shedding cover 35.

In my preferred form of construction the 110 housing 17 will be composed of a series of metallic overlapping plates, the adjacent edge of the outermost plate being provided with a marginal semi-circular shaped groove 17^a and being riveted to the inner overlapping plate on opposite sides of said groove by means of rivets 17^b-17^b and the housing is also preferably reinforced by means of transverse ribs, each rib comprising, as 115 shown in Fig. 3, a strip or bar of sheet metal having a U-shaped center portion 17^c and laterally extending flanges 17^d on opposite sides thereof, which flanges are riveted to the outer plating.

The construction above described constitutes a very rigid and light construction and 120 is suitable for use in any part of a metallic life boat though especially suitable for a housing such as herein described.

In Fig. 6 I have shown a slightly modified 130

form of construction which is similar in all respects to the construction above described except that the double bottom is omitted and air tanks 36 are provided beneath each of 5 the marginal seats and floor supporting members 37 are inserted at suitable places along the length of the well.

In Fig. 7 I have shown another slight modification in which the end of the housing, instead of having a single flat inclined face, as illustrated in Fig. 1, has two flat inclined faces 38—38^a terminating in a central line 39.

I also preferably provide observation 15 ports (not shown) at front and rear sides of the housing, which ports will be provided with stationary watertight closures.

Having described my invention, I claim:

1. A life boat embodying a hull having a 20 well and a housing erected above said well, entrance and exit ports provided with watertight closures, side ports having row-lock notches formed in their lower edges and a glazed watertight closure for each of such 25 side ports and notches.

2. A life boat embodying a hull having a well and a housing erected above said well,

entrance and exit ports provided with watertight closures, side ports having row-lock notches formed in their lower edges, a glazed 30 watertight closure for each of such side ports and an independent watertight closure for the row-lock notches hinged to the side port closures.

3. A lifeboat embodying a buoyant hull 35 having a seating compartment of substantially oblong, box-shape conformation and provided with a substantially flat bottom and substantially flat sides, buoyant fenders at the opposite sides of said seating compartment substantially coextensive in length with the said sides and also extending both above and below the water-line and a passenger-protective housing inclosing said seating compartment and having side walls extending 40 upwardly in a curve inclining inwardly from the sides of said hull.

In witness whereof, I have signed my name to the foregoing specification in the presence of two subscribing witnesses:

ANDREAS P. LUNDIN.
